(57) **CLAIM**

The ornamental design for a trailer door lock cover, as shown and described.

DESCRIPTION

FIG. 1 is a perspective view of a trailer door lock cover embodying our new design.

FIG. 2 is a top plan view thereof.

FIG. 3 is a side view thereof, as seen from the leftside of FIG. 1.

FIG. 4 is a bottom view thereof.

FIG. 5 is a side view as seen from the right side thereof, as seen from the right side of FIG. 1.

FIG. 6 is an end view thereof.

FIG. 7 is an end view thereof from the end opposite that shown in FIG. 6; and,

FIG. 8 is a perspective view of the bottom thereof, with portions broken away to illustrate the interior.
